(Cl. D26—5)

To all whom it may concern:

Be it known that I, Norman B. Murphy, a citizen of the United States, residing at West Englewood, County of Bergen, State of New Jersey, have invented a new, original, and ornamental Design for an Automatic Pilot Turn Control Unit for Aircraft, of which the following is a specification, reference being had to the accompanying drawings forming part thereof, in which:

Figure 1 is a front elevational view of an automatic pilot turn control unit for aircraft showing my new design;

Figure 2 is a side elevational view; and,
Figure 3 is a rear elevational view thereof.

I claim:

The ornamental design for an automatic pilot turn control unit for aircraft, as shown.

NORMAN B. MURPHY.
